UNITED STATES PATENT OFFICE.

JOHN V. ALLEN, OF WEYMOUTH, MASSACHUSETTS.

INNER SOLE.

SPECIFICATION forming part of Letters Patent No. 621,198, dated March 14, 1899.

Application filed February 18, 1898. Serial No. 670,836. (No model.)

To all whom it may concern:

Be it known that I, JOHN V. ALLEN, of Weymouth, in the county of Norfolk and State of Massachusetts, have invented certain new and useful Improvements in Inner Soles, of which the following is a specification.

This invention relates to inner soles, and particularly those adapted for use in welted boots and shoes, one side of the sole being cut along its margin to form a stitch-receiving channel or channels. The channeling of the sole reduces its thickness to a considerable extent, leaving the sole undesirably limp and flabby at its marginal portion.

15 My invention has for its object to stiffen the channeled portion of the sole without increasing its thickness; and to this end it consists in an inner sole having its channeled portion provided with pins extending from the 20 margin of the sole inwardly across the channel or channels cut therein, the pins being between the bottoms of the channels and the opposite side of the sole, as I will now proceed to describe.

25 Of the accompanying drawings, forming a part of this specification, Figure 1 represents a side view of a portion of an inner sole embodying my invention. Fig. 2 represents an edge view of the same. Fig. 3 represents a 30 section on line 3 3 of Fig. 1. Fig. 4 represents a view similar to Fig. 3, showing the sole after it has been channeled.

The same letters of reference indicate the same parts in all the figures.

35 In carrying out my invention I insert in the edge of an inner sole *a* a series of slender pins *b*, which are preferably of steel or other suitable metal and are of such diameter that they

can be inserted between the channels *b' b²* and the side of the sole opposite the side from 40 which the lips *b³ b⁴*, formed by the channels, project. The length of the pins is such that they project across the channeled portion of the sole, and they are placed sufficiently close together to cause them to stiffen the channeled portion and prevent bending or curling under the ordinary pressure to which it is subjected.

I prefer to insert the pins *b* before the operation of channeling the sole, but do not 50 limit myself in this particular.

The lips *b³ b⁴* are usually formed from the flesh side of the sole, and the pins *b* are therefore inserted in close proximity to the opposite or grain side of the sole. The grain-surface of the sole is sufficiently dense and firm to enable it to guide the pins as they are being driven and prevent them from being deflected through the surface of the sole in 55 closest proximity to them.

60 I claim—

1. A channeled inner sole provided with a series of stiffening-pins inserted in its edge and extending across the channeled portion.

2. An inner sole having a channel or channels formed in its flesh side, and a series of pins driven into the edge of the sole, between the flesh and grain-sides, the pins being in close proximity to and parallel with the grain side.

70 In testimony whereof I have affixed my signature in presence of two witnesses.

JOHN V. ALLEN.
